[57] CLAIM

The ornamental design for a clothes hamper, substantially as shown and described.

DESCRIPTION

FIG. 1 is a front perspective view of a clothes hamper showing my new design.

FIG. 2 is a top plan view thereof.

FIG. 3 is a front elevational view thereof.

FIG. 4 is an end elevational view thereof taken from the right side as viewed in FIG. 1, the opposite end being a mirror image thereof.

FIG. 5 is a rear elevational view thereof; and

FIG. 6 is a bottom plan view thereof.
